UNITED STATES PATENT OFFICE.

MALCOLM CURRY, OF SCARSDALE, NEW YORK, ASSIGNOR TO THE AMERICAN THREAD COMPANY, OF NEW YORK, N. Y., A CORPORATION OF NEW JERSEY.

WOUND SEWING-MACHINE BOBBIN.

Application filed February 3, 1926. Serial No. 85,871.

My invention relates to new and improved bobbins for use in sewing machines and the like, and has for its object to provide a new and improved bobbin having end pieces secured thereto by adhesive the end pieces covering the ends of the core and not reducing the internal diameter of the core.

The following is a description of an embodiment of my invention, reference being had to the accompanying drawings, in which:

Figure 1 shows in section a core with a mass of thread thereon to which the end pieces are to be applied;

Fig. 2 shows a central section of the complete bobbin;

Fig. 3 is an end view of the same.

Referring more particularly to the drawings 2 is a tubular core of cardboard or other suitable material. 4 is a mass of thread wound universally upon the core. 6 are perforated end pieces of cardboard or other suitable fibrous material which are secured to the tubular core at the ends 8 by adhesive.

The perforations in the end pieces are of the same diameter as the internal diameter of the core, so that the end pieces do not overlap or enter the core.

In producing the bobbin the mass 4' is wound upon the tubular core 2', the ends of the mass being somewhat curved as at 10. The product thus produced is then subjected to endwise compression which consolidates the mass somewhat and compresses the core so as to cause it to thicken at its ends, as shown at 12, bringing the ends of the core flush with the adjacent portions of the mass. The perforated end disks are then applied with sufficient adhesive to secure the same to the ends of the core only and with the axes of the perforations in line with the axis of the core and subjected to pressure to cause them to conform to the end surfaces of the mass.

Before application, the end pieces are embossed so as to be pre-formed into a concavo-convex shape, as shown in Fig. 2, provided with a flattened zone 14 about the orifice, whose inner face lies evenly on the end of the core so as to be easily secured by the ad-

hesive. The elevated portion 16 of the convex surface makes contact with the ends of the bobbin holder at a point removed from the core so as to provide suitable friction. The disks applied in this manner do not reduce the internal diameter of the core. The radius of the curvature of the concavo-convex portions of the disks is slightly smaller than the radius of the normal curvature of the ends of the mass when wound and also when first compressed and therefore the edges of the end pieces, when applied to the core and secured thereto, exert a spring tension upon the peripheries of the end surfaces of the mass so as to prevent the formation of spaces between the mass and the disks in which the thread being unwound may be liable to enter. The concavo-convex shape of the end pieces conforming substantially to the curvature of the end pieces of the mass when wound also tends to reduce the liability of the end pieces separating from the mass in the completed product so as to form such spaces upon an expansion of the mass.

In the production of these bobbins I preferably subject the core and mass to the preliminary compression as described so as to not only have the mass compressed but to thicken up the ends of the core and then apply the end pieces, although the end pieces may be applied before compression, if desired.

As will be evident to those skilled in the art, my invention permits various modifications without departing from the spirit thereof or the scope of the appended claims.

What I claim is:

1. A wound bobbin comprising a tubular core, a mass of thread wound universally thereon, and perforated end pieces of fibrous material secured by adhesive to the outer ends of said core so as to cover the same, said core being compressed axially and having its end portions thicker than its central portion on account of said compression the perforations in the end pieces being of the same diameter as the internal diameter of the core.

2. A wound bobbin comprising a tubular core, a mass of thread wound universally

100

thereon, and perforated end pieces of fibrous material secured by adhesive to the outer ends of said core, said core being compressed axially and its end portions thicker than its central portion on account of said compression, said end pieces having flattened zones contacting with the core ends and covering

the same, the perforations in the end pieces being of substantially the same diameter as the internal diameter of the core.

10

In testimony whereof, I have signed my name to this specification this first day of February, 1926.

MALCOLM CURRY.

thereon, and perforated end pieces of fibrous material secured by adhesive to the outer ends of said core, said core being compressed axially and its end portions thicker than its 5 central portion on account of said compression, said end pieces having flattened zones contacting with the core ends and covering

the same, the perforations in the end pieces being of substantially the same diameter as the internal diameter of the core. 10

In testimony whereof, I have signed my name to this specification this first day of February, 1926.

MALCOLM CURRY.

Certificate of Correction.

Patent No. 1,649,289.

Granted November 15, 1927, to

MALCOLM CURRY.

It is hereby certified that error appears in the printed specification of the above-numbered patent requiring correction as follows: Page 1, line 27, for the word "no" read "do"; and that the said Letters Patent should be read with this correction therein that the same may conform to the record of the case in the Patent Office.

Signed and sealed this 6th day of December, A. D. 1927.

[SEAL.]

M. J. MOORE,
Acting Commissioner of Patents.

Certificate of Correction.

Patent No. 1,649,289.

Granted November 15, 1927, to
MALCOLM CURRY.

It is hereby certified that error appears in the printed specification of the above-numbered patent requiring correction as follows: Page 1, line 27, for the word "no" read *do*; and that the said Letters Patent should be read with this correction therein that the same may conform to the record of the case in the Patent Office.

Signed and sealed this 6th day of December, A. D. 1927.
